JAR CAP

Anton George Jedlicka, Minneapolis, Minn., assignor to Hancock-Nelson Mercantile Company, St. Paul, Minn., a corporation of Minnesota

Application April 18, 1934, Serial No. 721,218

3 Claims. (Cl. 215—73)

This invention relates to jar closures and it has for its general object the provision of an improved jar cap of that type which seals against the inner edge of the jar.

One of the more specific objects of the invention is the provision of a jar cap with internal flexible sealing disk, so co-operably arranged as to inhibit rotation of the disk against the rough or irregular edge of the jar when the cap is screwed in place, whereby tearing of the disk is avoided and a better seal produced.

Another object of the invention is the provision of a jar cap having an opening in the center bounded by downwardly extending wall or flange which co-acts with the middle of the sealing disk, holding it spaced from the inside face of the cap, permitting the peripheral portions of the disk to camber under the pressure of the edge of the jar, producing pressure against 20 the edge of the jar which prevents rotation of the disk.

A further object of the invention is to provide a jar cap with open center and depending bounding flange as described, in combination with a flexible sealing disk which acts as a diaphragm, moving under the diurnal pressure changes within the jar, and thereby preventing diffusion of the air with gaseous contents of said jar, the disk exposing its maximum area to flexion when 30 the pressure of the atmosphere exceeds the pressure within the jar and presenting a minimum area to possible diffusion, when the pressure within the jar exceeds that of the atmosphere.

Still another object of the invention is the provision of a metal jar cap with paper sealing disk, the cap being open at the center to expose the disk which may be cut out or punctured to form a discharge opening, and in which the depending flange which bounds the opening, holds the 40 paper away from the metal avoiding corrosion of the latter and objectionable discoloration of the paper.

Still another object of the invention is to provide a jar cap of the type described having the 45 peripheral wall of the central opening threaded, adapting the cap to a secondary utility in connection with a spout, lamp burner, etc.

Other objects of the invention will appear as the following description of a preferred and practical embodiment thereof proceeds.

In the drawing which accompanies and forms a part of the following specification and throughout the several figures of which the same characters of reference have been used to denote identical parts:

Figure 1 is a plan view of a jar cap embodying the features of the present invention;

Figure 2 is a vertical diametrical section through the jar cap showing it partly screwed down on the mouth of a Mason jar; 60

Figure 3 is a similar view showing the cap entirely screwed down and illustrating in dotted lines the flexion of the paper disk when atmospheric pressure exceeds that within the jar;

Figure 4 is a vertical section showing the use 65 of the jar cap as an adapter between the mouth of the jar and a spout by means of which the contents of the jar may be discharged; and

Figure 5 is a similar view showing the jar converted into a lamp by screwing a common form 70 of burner into the central opening in the jar cap.

Referring now in detail to the several figures the numeral 1 represents a metallic cap comprising the substantially flat and annular top portion 2, provided peripherally with a down 75 turned and preferably integral flange 3 threaded as at 4 to receive the threaded mouth 5 of a glass jar. The cap is provided with a flexible paper disk 6 fitting therein, and preferably paraffined. The disk 6 is adapted to make sealing contact 80 with the edge of the jar mouth when the cap is screwed tightly in place. Caps with paper disks or linings adapted to seal against the inner edge of the jar mouth are known, but their use is more or less limited to those classes of goods which it 85 is not absolutely essential to seal in an air-tight manner, for example, pickles, preserves, etc.

The common defect of such jar caps is the tearing of the edge of the paper disk when the cap is screwed home due to the rotation of the disk upon 90 the rough or irregular edge of the jar mouth. It is thus practically impossible to get a good seal and the vinegar or other liquid content of the jar is apt to leak out, staining the label, corroding the outside of the lid and otherwise impairing 95 the respectability of the jar. The fact that a good seal cannot be uniformly obtained also renders such jar caps ineligible for the packaging of aromatic substances, such as coffee which ordinarily lose much of their flavor due to the escape of 100 aromatic gases evolved in the jar or container.

The present invention provides a better seal by preventing the rotation of the disk 6 upon the edge of the jar mouth thereby avoiding tearing of the paper disk. This it does through the formation of a central opening 7 in the jar lid and the bent down margin of the cap which bounds said opening forming a flange 8. The lower edge of this flange preferably lies in a transverse plane 105 and normally engages the paper disk 6 holding it 110

spaced from the annular top portion 2. When the cap with the disk is screwed down on the jar, it is obvious from Figure 2 that the peripheral portions of the disk are forced out of their planar relation to the central portion by the incursion of the edge of the jar creating a pressure between the disk and the edge of the jar mouth. Of course, an equal pressure is generated along the line of contact between the edge of the flange 8 and the disk, but since the circumference of the flange 8 is much less than the circumference of the jar mouth and the flange 8 presents an edge contact to the disk while the jar presents a flatter surface, the disk will be held fixed in its relation to the mouth of the jar, the disk remaining stationary while the cap is rotated to its final position of tightness in which position, the peripheral edge of the disk is clamped between the edge of the jar mouth and the top portion of the cap. The inequalities or irregularities of the edge of the jar thus bury themselves into the paper disk under the clamping pressure, perfecting the seal instead of tearing their way circumferentially through the paper as is inevitably the case where the disk rotates.

Another virtue of the cap of the present invention which particularly adapts it to a coffee package is illustrated in Figure 3. It will be understood from what has been stated in relation to the objects of the invention that even though coffee may be packed in a vacuum, this vacuum is gradually supplanted by a gas, being the volatilized aromatic principle of the coffee and the loss of which materially deteriorates the quality of the coffee. If the jar of coffee is closed by an inflexible lid, the pressure of the atmosphere in the coolness of the night when the contents of the jar contract ordinarily causes leakage of the atmosphere into the jar diluting the aromatic gas, and in the warmth of the daytime, the building up of pressure within the jar can ordinarily be relieved only by the leakage from the jar of some of the gaseous contents. If the closure is flexible so that it functions as a diaphragm, the contraction and expansion of the jar can be accommodated without necessitating leakage or diffusion.

It will be observed from Figure 3 that when the atmospheric pressure exceeds the pressure within the jar the paper disk is forced inwardly away from the flange 8 so that its entire area is exposed to atmospheric pressure and allowing a maximum degree of flexibility, but that when the pressure within the jar exceeds atmosphere, the paper disk 6 contacts with the edge of the flange 8 reducing the area upon which the differential pressure can act, to the size of the opening 7 so that only this small area is subject to osmotic pressure. Consequently, not only in view of the perfect seal between the disk and the edge of the jar mouth, but also in view of the differential diaphragm action of the disk 6, the loss of aroma from the coffee package is reduced to a minimum.

It will be observed from Figures 2 and 3 that the flange 8 holds the paper disk 6 out of contact with the major portion of the surface of the metal cap thus, in the event that the cap may become moist from the liquid contents of the jar, preventing corrosion of the metal and discoloration of the disk. This is a feature particularly advantageous in the packing of preserves or pickles.

The provision of the central opening 7 exposes the paper disk 6, affording a convenient means for gaining access to the jar by merely puncturing or cutting out the exposed portion of the disk, thereby forming a discharge opening.

The flange 8 is preferably threaded as indicated at 9, so that after the cap has served its primary function as a leak-proof closure for a jar, it may still serve other useful purposes. For example, a spout 10 as shown in Figure 4 may be threaded into the central opening and convert the jar, or any jar for that matter with which the cap may be used, into a dispensing container for lubricating oil or the like, or by screwing a well known form of burner 11 into the opening 7, the jar together with the cap and burner 106 become a complete kerosene lamp.

While I have in the above disclosure described what I believe to be a preferred and practical embodiment of my invention, it will be understood that the specific details of construction as shown and described are merely exemplary and not to be construed as limiting the scope of the invention as claimed.

What I claim is:

1. Jar cap comprising in combination, a metallic portion having a threaded peripheral flange adapted to be screwed upon a threaded jar mouth, said metallic portion having a central opening bounded by an inwardly extending flange, and a flexible disk fitting within said cap with its central portion engaging said flange and adapted to have its peripheral portion pressed into sealing relation between the top portion and the edge of a jar mouth, when the cap is screwed upon said jar.

2. Jar cap as claimed in claim 1, the inwardly extended flange being threaded.

3. Jar cap adapted to cooperate with the threaded mouth of a glass jar and a paper disk laid upon the edge of the mouth of said jar, comprising a metallic member having an annular top portion, a threaded flange extending downwardly from its outer periphery adapted to engage the threaded mouth of the jar, and a threaded flange extending downwardly from its inner periphery and adapted to engage the paper disk and bulge the same downwardly as the cap is screwed in place, preventing rotation of the disk and maintaining the major portion thereof spaced from the annular portion of said cap.

ANTON GEORGE JEDLICKA.
